UNITED STATES PATENT OFFICE.

HENRY G. ROTH, OF MINNEAPOLIS, MINNESOTA.

DESIGN FOR A DISPLAY-FIXTURE FOR STORES.

SPECIFICATION forming part of Design No. 31,528, dated September 19, 1899.

Application filed July 17, 1899. Serial No. 724,145. Term of patent 7 years.

To all whom it may concern:

Be it known that I, HENRY G. ROTH, a citizen of the United States, residing at Minneapolis, in the county of Hennepin, Minnesota, have invented and produced a new and original Design for a Display-Fixture for Stores, of which the following is a specification, reference being had to the accompanying drawing, forming a part thereof.

○ In said drawing the single view is a perspective with some parts broken away, illustrating a display-fixture for stores embodying my invention.

As therein shown, the leading or material features of my design are the columns *a*, the capitals or head-pieces *b*, the arch or connecting plates *c*, and the cove-plates *d* and *e*, with the said parts disposed in respect to each other, as shown.

○ The columns *a* are represented as rising from the top member of the display-shelving, 1 and as made up of a series of sections.

The capitals *b* are of circular form.

The arch or connecting plates *c* are under-
25 cut on curved lines intersecting with each other, so as to give an effect from the arch-plate somewhat similar to drapery. The cove-plates *d* and *e* coöperate to form a cornice surmounting the arch-plates *c*. The cove-plates
30 *d* and *e* are both of curved or concave form;

but the member *e* surmounts the member *d*, and rises therefrom nearly in a vertical plane, so as to give therefrom a retreating effect in respect to the cove *d*.

The head-pieces *b*, the arch-plates *c*, and the 35 cove-plates *d* and *e* are in practice covered with paint or paper in suitable contrasting colors.

With the said parts *a*, *b*, *c*, *d*, and *e* disposed as above described a colonnade canopy 40 is afforded to the display-shelving, which adds greatly to the artistic effect. This design is especially intended for use in grocery and other stores, surmounting shelving for displaying canned and bottled goods.

The face-surfaces of the plates *b*, *c*, *d*, and *e* may be utilized for display-cards advertising the different kinds of goods.

Having thus described my invention, what I claim as new, and desire to secure by Letters 50 Patent of the United States, is as follows:

The design for a display-fixture for stores, substantially as herein shown and described.

In testimony whereof I affix my signature in presence of two witnesses.

HENRY G. ROTH.
